UNITED STATES PATENT OFFICE.

WALLACE A. BARTLETT, OF WASHINGTON, DISTRICT OF COLUMBIA.

PNEUMATIC CANNON.

SPECIFICATION forming part of Letters Patent No. 294,352, dated March 4, 1884.

Application filed January 8, 1884. (No model.)

To all whom it may concern:

Be it known that I, WALLACE A. BARTLETT, residing at Washington, in the District of Columbia, have invented certain new and useful 5 Improvements in Pneumatic Cannon, of which the following is a specification, reference being had therein to the accompanying drawings.

This invention relates to pneumatic or other 10 guns in which the projectile is driven by the pressure of an elastic gas which is admitted from some supply outside the gun-tube.

The invention consists in the construction and arrangement of the gun and flask; the 15 mode of operating the valve which governs the admission of air or gas to the gun, and the mechanism therefor; the mechanism for training the gun, and in details and combinations as hereinafter pointed out in the claims.

20 The object of the invention is to provide a gun from which projectiles loaded with dynamite or other high explosives may be fired without danger of bursting in the gun.

In the drawings, Figure 51 is a longitudinal 25 section of the gun and a plan of the flask which forms the carriage. Fig. 52 is a side elevation of the gun and a section of the flask and training-cylinder. Fig. 53 is a transverse section on irregular line $x^5 x^5$. Fig. 54 is a vertical 30 transverse section of the gun and training-cylinder. Fig. 55 is an elevation of same. Fig. 56 is a side elevation, showing the connection by which the automatic cut-off is operated. Fig. 57 is a horizontal section of the cut-off 35 valves. Fig. 58 is a section of the breech of the gun, showing projectile-detent.

The gun tube or barrel 1⁵ has a breech-closing mechanism of usual form, and is strengthened by a web, 2⁵, or in other manner. The 40 air-supply is from the flask 3⁵, which forms the carriage on which the gun is mounted. The gun-tube 1⁵ has hollow trunnions i^5 just forward of the breech-closing apparatus, and has trunnion-supports 4⁵, which are hollow, and connect 45 with the flask 3⁵. Compressed air or gas from the flask has access to the gun through the trunnion-supports and trunnions when the valve is open. The gun-tube is supported at a suitable distance forward of the trunnions by suitable mechanism for elevating and depressing the same. This, as illustrated, is a cylinder, 50 a^5 , which communicates with the flask through

the valve-box 5⁵. The cylinder contains a piston, which, by its rod 6⁵, supports the gun, the said gun or its web resting in a saddle, 6⁵. 55 Thus the gun may be raised by opening the valve in 6⁵ and permitting the gas-pressure to act upon the piston. As the gun must turn on its fixed trunnions, a longitudinal movement must be allowed on the saddle 6⁵. The 60 valve in box 5⁵ may be a common slide-valve, operated by a lever or handle, 6⁵, from near the breech of the gun. The air or gas is permitted to pass to the gun-tube 1⁵ through the trunnion-supports 4⁵ when the valve 6⁵ is 65 opened. This valve in valve-box 5⁵ opens and closes communication between the flask and trunnion-supports. Valve 6⁵ has a stem, K⁵, connected to a piston, m⁵, in cylinder 6⁵, so that the valve may be operated by the pressure of 70 gas on the said piston. Compressed air or gas from the flask is admitted to cylinder 6⁵ by means of the slide-valve o⁵, which is moved by a pressure in pipe p⁵. The pipe p⁵ communicates with a small cylinder, q⁵, near the muzzle of the gun, or with other actuating mechanism near the muzzle. The pipe may be filled 75 with oil, which will act as a piston, or may be simply a pneumatic tube operating by air-pressure, all as more fully described in other 80 applications filed in the United States Patent Office of even date herewith, which applications are herein referred to as more fully explaining the operation of some features of this device, and as making claims to some of the 85 features herein shown and described but not herein claimed.

A detent, r⁵, is illustrated in Fig. 58. This may be simply a spring or catch arranged in a groove near the breech of the gun. A projectile passed into the gun from the breech will press down the spring, which will rise as soon as the projectile is past and prevent the projectile from sliding back to stop the entrances for the air or gas from the flask. The 90 flask may be pivoted at s⁵, which pivot forms a means of communication through which compressed air or gas may be forced into the flask. The gun is traversed by swinging the flask, which forms a carriage therefor. 100

When a projectile is put into the breech of the gun forward of the apertures i⁵, it is held from sliding back, should the muzzle be elevated, by the catch r⁵. Now, supposing the

flask to be charged with gas at a high pressure, the slide-valve o^5 is actuated (by hand or otherwise) to admit air to cylinder t^5 , and so open the valve h^5 . This opens communication 5 from the flask to the gun-tube and drives out the projectile. As the projectile reaches the muzzle, it actuates the mechanism leading through pipe p^5 to the slide-valve and shifts 10 said valve, so that the piston m^5 is moved in the other direction and the valve which governs the supply to the gun is closed.

The connections for shifting valve o^5 may 15 be pneumatic, electric, or mechanical, as described in other applications referred to, or the valve o^5 may be operated in both directions by hand, or by electric or clock-work mechanism which is not actuated by the projectile, the principal feature of this part of my invention being that the operating-valve 20 is itself operated by gas-pressure from the flask. It is obvious that the same mode of manipulation will apply to a rotary as to a slide valve.

The apparatus for raising or depressing the 25 muzzle of the gun need not be arranged at the muzzle end. On a counterpoised gun it would obviously be differently placed, and the piston can of course be driven in either direction in manner well known to mechanics.

30 I claim—

1. A gas-flask forming the gun-carriage, a gun-tube supported thereon by a support independent of the trunnions, substantially as described, and hollow trunnions and trunnion-supports near the breech of the gun, through 35 which communication may be had from the flask to the gun, all combined substantially as set forth.

2. A gas-flask forming the gun-carriage, and 40 having a passage leading to the bore of the gun, in combination with mechanism, substantially as described, whereby the pressure of gas from the flask is made to elevate the gun.

3. The combination, with a gas-flask and a 45 gun-tube mounted thereon, and having communication with the flask through the trunnions, of a cylinder and piston arranged to elevate and depress the gun by the pressure of gas from the flask, substantially as described.

4. The combination, with the gas-flask and 50 supply-pipe of a gas-pressure gun, of a valve which controls the passage between said flask and pipe, and mechanism, substantially as described, whereby the pressure of gas in the flask may be made to actuate said valve, substantially as set forth.

5. The combination, with the gas-flask and the supply-pipe of a gas-pressure gun, and a valve controlling the passage between the same, of an operating cylinder, piston, and 60 valve, by which the first-mentioned valve may be operated by means of gas-pressure, substantially as described.

6. The combination, with the gas-flask, supply-pipe, and valve controlling the supply, arranged to co-operate as described in a gas-pressure gun, of operative mechanism, substantially as described, whereby the valve may be shifted by the pressure of air from the flask, and mechanism, substantially as described, 70 leading therefrom, by which the same may be controlled, as set forth.

7. The method herein described of closing the operating-valve automatically, which consists in actuating mechanism by the passage 75 of the projectile through the bore, which in turn throws into operation mechanism actuated by the pressure of gas in the flask, substantially as stated.

8. The combination, with the gas-flask, the supply-pipe, and valve controlling the passage between the two, of mechanism, substantially as described, whereby the pressure of the gas in the flask may be made to operate the valve, and mechanism leading therefrom 85 to near the muzzle of the gun, by which the gas-pressure may be operated to close the valve as the projectile leaves the gun, as set forth.

In testimony whereof I affix my signature in 90 presence of two witnesses.

WALLACE A. BARTLETT.
